(57) **CLAIM**

I claim the ornamental design for the jewelry, as shown and described.

DESCRIPTION

FIG. 1 is a front view of the jewelry;

FIG. 2 is top view of the jewelry;

FIG. 3 is a bottom view of the jewelry;

FIG. 4 is a right side view of the jewelry; and,

FIG. 5 is a left side view of the jewelry.

The broken line showing of the central stone and inner rings of stones represents unclaimed portions of the jewelry and forms no part thereof.
